Inventor:

Maxwell Case,
by Wallace R. Lane.

Attest:

UNITED STATES PATENT OFFICE.

MAXWELL CASE, OF EVANSTON, ILLINOIS.

CHART FOR RECORDING COMPETITIVE SALES.

Application filed October 16, 1920. Serial No. 417,399.

To all whom it may concern:

Be it known that I, MAXWELL CASE, a citizen of United States, residing in Evanston, in the county of Cook and State of Illinois, have invented certain new and useful Improvements in Charts for Recording Competitive Sales, of which the following is a specification.

The purpose of my invention is to so record the sales of a plurality of salesmen, that they will all be able to see at a glance what each one is doing, and will be spurred on to make additional sales; also to so record the sales made by a plurality of salesmen, during a sales competition, that one can see at a glance who is doing the best work, and who is not doing well; also to produce such a chart as will show at a glance the effect of the competition upon the sales made by the salesmen; and such further objects, advantages, and capabilities as will later more fully appear.

My invention further resides in combination, construction, and arrangement of parts illustrated in the accompanying drawings, and while I have shown therein a preferred embodiment, I desire the same to be understood as illustrative only, and not as limiting my invention.

In the accompanying drawings, illustrating my invention, Fig. 1 illustrates the chart of my invention, partly filled in, and Fig. 2 represents a portion of one corner of said chart on a larger scale to show the effect of the coloring.

For the effective carrying out of my process, a suitable chart is provided having an appropriate heading, and comprising a plurality of vertical columns, and horizontal rows of spaces in which entries may be made. As shown in the drawings the left hand column, is used to designate what is to be entered in the rows extending to the right thereof, except that the third entry in this column explains the entries below. The first space in this column is marked "Route" though for a selling contest of a somewhat different type than that here illustrated this heading might be different, and might be used to indicate "Salesman". The word "Route" is used in the claims in a generic sense, i. e., to designate a given territory, the persons in that territory who are served, the salesman employed in that territory, or merely as a convenient mode of designating a salesman. The second

space in the left hand column is designated "Base," and means that the figures to the right thereof show the normal amount of sales for the route or salesman indicated. 60 In the particular example illustrated the time is divided up into periods of one week, ending on the date indicated under the title "Week ending." The numerals to the right of these entries indicate the amount 65 of sales made on the particular route or by the particular salesman, designated by the number at the head of the column.

When a sales period, for example, the week ending Nov. 16th, has closed, the numerals indicating the sales for the different salesmen or on the different routes are entered up opposite "Nov. 16th" and then the spaces in this row are colored in accordance with the previously adopted color scheme, 75 and according to whether or not the amount of sales are above or below "Base." Under route 9, we find that "Base" is 126, and that the sales for this week were 126 units. The particular example illustrated represents a milk competition sale, and in this competition a quart of milk counts a certain number of points, a pint of milk a different number of points, etc. In the competition illustrated blue includes "Base" 80 and any number of points up to, but not including 10 higher than base, red indicates anything below base, green, anything from 10 to 19 above base, gold anything from 20 to 49 above base, while uncolored 85 represents 50 or more above base.

Referring to Fig. 2, in which the colors are shown, it will be seen that the man on route 9, for the first week of the contest, made exactly "Base" or the normal amount 95 of business, that is 126 points. The next week he made 131, the next 130, the next 139, the next 135, etc. In other words for the first three weeks he did not reach ten above "Base," but in the fourth week he 100 made thirteen above "Base" and therefore this space is colored green. The next week he made only nine above "Base" and this space is colored blue; the next week he made sixteen above "Base" and therefore green 105 is entered in this space; the next week he made only six above "Base" and therefore returned to blue; while in the eighth period of the contest he fell below "Base" and therefore his color is red. After this he 110 gradually increased his sales to green and gold up to "Clear."

Column 3 shows that on route 10, in which "Base" or the normal amount of business is 234, the salesman for the first week fell below "Base", and that after this he gradually increased his sales to blue, green and gold, but did not however reach "Clear". It will be seen by reference to column 35, headed 56, designating route or salesman 56, that "Base" is 168 points, and that this "Base" was, at no time during the contest, reached by this salesman. This column should therefore be entirely colored red.

Owing to the smallness of the spaces in Fig. 1, and the confusion which would result from coloring all of these spaces, only a small part have been colored, but an inspection of the numbers will show that during the first week of the contest approximately one half of the salesmen are recorded as being below "Base", while in succeeding weeks a smaller and smaller proportion are thus recorded, while the number entitled to green and gold constantly increases, until at the end of the contest, out of 38 contestants, there are only three reds, three blues, and five greens, the remainder being all gold, except in column number 9. This effect is more clearly shown in the right hand column which shows that the average "Base" was 160, that for eight weeks the average sales did not reach ten above "Base", but that in the ninth week this point was reached. It then took six weeks to make an average gain of ten points more, while in the next five weeks there was a gain of twelve points, thus showing in a very marked manner the effect of the contest on the sales. This method of recording the sales, has, as will be seen, a very salutary effect upon the work done by the salesmen, while this chart enables the person in charge of the contest to readily show in a graphic manner what the various salesmen are doing.

It should perhaps be noted that if a route is divided or a transfer is made, it will be necessary to start with a new "Base". Besides milk sale contests, among the various things to which this system may be adapted are insurance sales contests, ordinary merchandising contests, etc.

It will of course be understood that certain changes will be necessary and may be resorted to, to adapt this system to selling contests for various commodities, and that

such changes may be made without departing from the spirit of my invention as set forth in this specification, and the appended claims. It is also obvious that the positions of the date spaces and the "Route" and "Base" spaces may be interchanged without departing from the spirit of the claims.

Having described my invention:

I claim:

1. Means for indicating volume of business, comprising a chart divided into spaces arranged in intersecting columns and rows, one row containing "Route" indicating marks, another row indicating previous maximum sales for those "Routes" reduced to a basic standard and located in corresponding columns, and the remaining rows representing successive equal periods of time, this chart having therein in the designated intersecting columns and rows, numerals designating the "Route" sales for the period covered, expressed in terms of the above mentioned basic standard.

2. Means for indicating volume of business, comprising a chart having intersecting columns and rows, one of which has "Route" indicating designations, another of which has designations located in spaces corresponding to the "Route" designations and indicating the "Routes" previous maximum volume of business, a third of which has designations indicating successive periods of time, the remainder having color designations to indicate variations in the volume of business of the indicated "Route" for the successive periods of time.

3. Means for indicating volume of business, comprising a chart having intersecting columns and rows, one of which has "Route" indicating designations, another of which has designations indicating those "Routes" previous maximum volume of business, said designations being located in aligned spaces, a third of which columns or rows has designations indicating successive periods of time, the remainder having numerical and color designations at the intersections of the columns and rows to indicate respectively the volume of business and variations in the volume of business of the indicated "Route," the volume of business being expressed in terms of an arbitrary standard.

In witness whereof, I hereunto subscribe my name to this specification.

MAXWELL CASE.
